UNITED STATES PATENT OFFICE.

JOHN HARRIS, OF CLEVELAND, OHIO, ASSIGNOR TO THE J. HARRIS CO.,
OF CLEVELAND, OHIO.

ACETYLENE-GAS BURNER.

No. 823,329.

Specification of Letters Patent.

Patented June 12, 1906.

Application filed September 11, 1905. Serial No. 277,842.

To all whom it may concern:

Be it known that I, JOHN HARRIS, residing at Cleveland, in the county of Cuyahoga and State of Ohio, have invented a certain new 5 and useful Improvement in Acetylene-Gas Burners, of which the following is a full, clear, and exact description, reference being had to the accompanying drawings.

My invention relates to illuminating-burners, and particularly to burners wherein illumination is produced by an incandescent mantle. In operating burners of this class with acetylene gas difficulty has been experienced, owing to the liability of the parts to 10 become heated, thereby causing polymerization of the gas with the production of a smoky flame which carbonizes the mantle, and, further, owing to the liability of the gas to "light back" or burn at the gas-supply 15 nipple or within the passages leading from the nipple to the space below the mantle.

The object of the invention is to produce a burner which shall be free from the above defects and which shall be simple and economical in construction and reliable in operation.

Referring to the drawings, Figure 1 represents a vertical section through a burner embodying my invention; and Fig. 2 represents a perspective view, with parts broken away, 20 of a portion of the burner proper.

Describing the parts by reference-numerals, 1 represents a nipple of ordinary construction provided with an interior screw-thread 2 for connection with a gas-supply 25 pipe and with the discharge-orifice 3 at the upper end thereof. This nipple is provided with a reduced exteriorly-threaded portion 4, to which is screw-threaded the mixing-tube 5. This tube is provided with one or more 30 air-inlet openings 6, said openings being controlled by a sleeve 7 of ordinary construction mounted on said tube. Within the bore of the tube 5 there is inserted a reducing-sleeve 8, the base of said sleeve being slightly above 35 the openings 6 and the upper end of the sleeve terminating some distance below the top of said tube 5. 9 represents a tube telescopically supported on the tube 5 and carrying the burner proper. The lower end of the 40 tube 9 is flanged outwardly to support the gallery 10, and the upper end of said tube is flanged outwardly at 11 to support the lower 45 end of the burner-casing 12, such lower end

extending somewhat below the top of the mixing-tube 5, said casing 12 being of considerably-greater diameter than said tube and having its lower end flanged inwardly at 13 to engage the upper end of the tube 9. A spider 14 is supported below a bead 15 on the casing 12, the lower ends of the arm of said 50 spider being turned outwardly at 16 to engage the annular shoulder 18 of the gallery, which supports the chimney 17.

Within the casing 12 is placed the tubular body or member 19, said body or member being spaced a short distance (about one-sixteenth of an inch) from the adjacent inner wall of the casing 12 to form a restricted passage therewith for the major portion of its length. The member 19 may be centered 65 and supported operatively to the member 12 by having the lower end 20 thereof spun outwardly to engage the inner wall of said member and telescope therein. This enlarged 70 lower portion of the member 19 is of such length as to bring the contracted portion thereof slightly above the top of the tube 5. The upper end of the member 19 is closed, as by an integral cap 21, said cap being conical and slightly concaved on its exterior surface. 75 A corresponding cap 22 is provided for the upper end of the casing 12, said cap being preferably removably fitted thereto and provided with a restricted orifice 23, at the upper extremity thereof. This cap is also preferably concaved exteriorly thereof, and the parts are so arranged as to provide a comparatively narrow space (about one-eighth of an inch) between the caps. The restricted portion of the member 19 between the cap 21 80 and the base 20 is provided with the horizontally-arranged slits 24. Two sets of such slits are provided, sufficient space being left between the adjacent ends of the two sets of slits to prevent undue weakening of the member. A mantle 25 is supported in operative 85 relation to the cap 23 in any desired manner, as by the ordinary supporting-wire 26.

With the parts as above described the operation is as follows: Gas passes through the 90 connection 1 and nipple 3 into the restricted bore 8, the air-supply valve being set to furnish the proper proportion of air through the slots 6. In the case of acetylene the proportion of air to gas will be thirteen to one. The 95 size of the restricted bore 8 is such as to per-

mit the mixture of gas and air to flow without friction into the enlarged upper portion of the tube 5 and into the mixing-chamber formed within the member 19, at the same time maintaining the proper proportion between the air and gas to insure proper combustion.

An important part of my invention resides in the width of the slits 24, which are formed in the tubular member 19. I have found that the width of these slits should be that of the thickness of 27-gage metal. If the width be increased, even to the thickness of 26-gage metal, there is danger that the mixture will light back within the interior of the tubular member 19. If, on the other hand, the width of these slits is lessened, even to the thickness of gage metal, the flame produced by the burner will be smoky. With the slits of the thickness specified, however, neither one of these objectionable results will be produced. From the slits 27 the mixture flows through the narrow space between the member 19 and the burner-casing 12 into the space between the caps 21 and 23 and is ignited above the orifice 23. The shallowness of the space between the member 19 and casing 12 further resists the tendency to light back. Furthermore, the upper extension of the tip 27 of the cap 21 resists such lighting back, as when flame of a reducing character strikes the tip 27 it is immediately extinguished. It will be seen, therefore, that I provide three checks against the danger of lighting back one within the space between the caps 21 and 22, one between the vertical walls of the tubular member 19 and sleeve 12, and the third by the provision of the slits 24 of such width as to prevent flame from passing therethrough.

In addition to preventing lighting back the narrow space between the member 19 and the casing 12 and the supplying of the fuel mixture therethrough accomplish another important result. The mixture of gas and air supplied through the slits flows in contact with the walls of the member 19 and casing 12, thereby cooling the same. The sleeve 12 is further cooled by the upward flow of air in contact with the outer surface thereof produced by the draft of the burner. This cooling of the outer surface may be increased by applying to the same and the cap 22 a coating of powdered material which is non-combustible at the temperature of an atmospheric burner. This material is represented at 28 and being powdered the air-spaces formed between the particles thereof prevent in a great measure the conduction of heat down the burner-cap and the sleeve or casing 12. There are thus provided three means for cooling the burner-casing or sleeve—viz., the application of a cool stream of gas and air to the inner wall thereof, the coating of the outer wall with non-conduct-

ing material to prevent in a great measure the heating of said wall by the conduction from the top of the burner-cap, and the flow of air against said outer wall produced by the draft through the burner. The cooling of the burner-casing 12 effectually prevents the polymerization of the acetylene and the formation of benzene, which being incompletely combustible at the temperature of an atmospheric burner burns with a smoky flame, producing carbonization of the mantle. This polymerization of the gas, which is one of the most serious drawbacks to the use of acetylene in burners of the type herein shown, is entirely avoided by my construction.

Having thus described my invention, what I claim as new, and desire to secure by Letters Patent, is—

1. A gaseous-fuel burner comprising a hollow body forming a mixing-chamber, said body having one end thereof closed by a tapered cap, means for supplying gaseous fuel to the interior of said body, a burner-casing communicating with said body, said casing having a tapered cap, spaced from the former cap to provide a restricted passage-way therebetween and provided with a central perforation, substantially as specified. 85

2. In a gaseous-fuel burner, the combination of a mixing-tube, a tubular member of greater diameter than said tube surrounding the discharge end of the same and having its opposite end closed by a tapered cap, said cap terminating in a point, a casing surrounding said tubular member and extending beyond the end of the same, said casing having a tapered cap thereon provided with a central discharge-orifice in axial alignment with the point of the cap on the said tubular member, said member having a discharge orifice or orifices communicating with the interior of the casing, substantially as specified. 95

3. A gaseous-fuel burner comprising a mixing-tube, a tubular body into one end of which said tube projects and having at its other end a cap, a burner-casing surrounding said body and spaced a short distance therefrom to form a restricted annular passage-way, said body being provided with narrow slits communicating with said passage-way, and a cap for said casing spaced a short distance from the former cap and having therein a burner-opening, substantially as specified. 110

4. A gaseous-fuel burner having in combination a mixing-tube, a tubular body into one end of which said tube discharges, a cap for the other end of said body, a burner-casing surrounding said body and forming therewith a restricted annular passage-way, said body being provided with a series of narrow slits arranged transversely thereof and communicating with said passage-way, said series extending from the upper portion of said 125 130

body to near the lower end thereof, and a burner-cap on the burner-casing provided with a restricted outlet, substantially as specified.

5. A gaseous-fuel burner comprising a mixing-tube, a tubular member surrounding the discharge end of said tube and having its opposite end closed by a tapering cap and provided with lateral slits intermediate said cap and the discharge end of the mixing-tube, a sleeve surrounding said tubular member and forming therewith a restricted passage-way with which said slits communicate, a cap on said sleeve corresponding in contour to the first-mentioned cap and having a restricted discharge-orifice therethrough, substantially as specified.

6. A gaseous-fuel burner comprising a tubular body forming a mixing-chamber, said body having a conical cap at one end thereof and a plurality of outlets through the wall thereof, means for supplying gaseous fuel to the interior of said body, a tubular burner-casing surrounding said body and forming therewith a restricted annular passage for the gaseous mixture supplied through said outlets, a conical cap on said casing provided with a central perforation therethrough, said cap being substantially parallel with the former cap and forming therewith a restricted passage-way, substantially as specified.

7. A gaseous-fuel burner comprising a mixing-tube, a hollow tubular body of greater diameter than said mixing-tube in axial alinement therewith, into the lower end of which said mixing-tube projects, a cap for the upper end of said body, said body being provided with a series of narrow transverse slits extending from below the cap to a point substantially in line with the top of the mixing-tube, a tubular burner-casing surrounding said tubular member and spaced a short distance therefrom to provide a restricted passage-way the lower end of which extends as far as the lowest slit in said member, and a cap on said casing having a central perforation therethrough, said cap being substantially parallel with the former cap and forming a restricted passage-way therewith, substantially as specified.

8. In a gaseous-fuel burner, the combination of a mixing-tube, a tubular member into one end of which said tube projects, a conical cap closing the opposite end of said member, the outer surface of said cap being concave, a burner-casing closed at its lower end and surrounding said member to form therewith a restricted annular passage-way, the upper end of said casing extending beyond the top of the vertical side wall of the said member, a cap at the upper end of said burner-casing corresponding in contour to the cap on said member and having a central perforation therethrough, said member being provided with a series of openings extending from be-

low its cap to a point opposite the bottom of the annular passage-way, substantially as specified.

9. A gaseous-fuel burner having in combination an inner hollow body provided with a series of slits of the width of the thickness of twenty-seven-gage metal, and an outer casing receiving the fuel discharged through said slits, substantially as specified.

10. A gaseous-fuel burner comprising a casing having at one end a burner-orifice, means for directing gaseous fuel in contact with the inner wall of said casing in its passage to said orifice, and a coating of non-conducting material applied to the outside of said casing, substantially as specified.

11. In a gaseous-fuel burner, the combination of a mixing-tube, a vertically-extending burner-casing in communication with said mixing-tube, a perforated cap carried by said casing, a mantle in operative relation thereto, a gallery having openings in the lower portion thereof permitting the upward flow of air past said burner-casing, and a coating of powdered material carried by said casing, substantially as specified.

12. A gaseous-fuel burner comprising a vertically-arranged burner-casing having a burner-opening in the upper end thereof, a mantle supported in operative relation to said burner-opening, a perforated gallery below said casing, a chimney carried by said gallery, means for directing gaseous fuel in contact with the inner wall of said casing in its passage to the burner-opening, and a coating of non-conducting material applied to the outer wall of said casing, substantially as specified.

13. In a gaseous-fuel burner, the combination of a mixing-chamber, said chamber having its upper end closed by a tapered cap, a casing or sleeve surrounding said chamber and extending beyond the end of the same, said casing or sleeve having a tapered cap thereon provided with a central discharge-orifice in axial alinement with the point of the cap on the mixing-chamber, said mixing-chamber having a discharge orifice or orifices communicating with the interior of the sleeve or casing, substantially as specified.

14. A gaseous-fuel burner comprising a mixing-chamber having the upper end thereof closed by a tapered cap and provided with a discharge orifice or orifices in the body thereof, a sleeve or casing surrounding said chamber and forming therewith a passage-way with which said orifice or orifices communicate, said passage-way having a restricted outlet, a cap on said sleeve or casing having a central restricted discharge-orifice therethrough, said caps being spaced a short distance apart to provide a restricted passage-way therebetween, substantially as specified.

15. In a gaseous-fuel burner, the combina-

- tion of a mixing-tube, a vertically-extending burner-casing in communication with said mixing-tube, a perforated cap carried by said casing, a mantle in operative relation thereto, 5 a gallery having openings in the lower portion thereof permitting the upward flow of air along and past said burner-casing, and a coating of non-conducting material carried by said casing, substantially as specified.
- 10 16. A gaseous-fuel burner having in combination a discharge-orifice, a chamber communicating therewith, said chamber having a tapered cap, a burner-casing in communication with said chamber and having a tapered 15 cap provided with a discharge-orifice in alignment with the point of the cap on the chamber, substantially as specified.
17. A gaseous-fuel burner having in combination a discharge-orifice, a chamber communicating therewith, said chamber having a tapered cap, a burner-casing in communication with said chamber and having a tapered 20 cap provided with a discharge-orifice in alignment with the point of the cap, said caps being spaced a short distance apart to provide a 25 restricted passage-way therebetween, substantially as specified.
18. A gaseous-fuel burner having in combination a discharge-orifice, a chamber communicating therewith and provided with discharge-outlets in the side wall thereof, a
- burner-casing forming with said chamber a passage-way having a restricted outlet for the fuel discharged through the chamber, and a cap for said chamber having a central outlet, substantially as specified. 35
19. A gaseous-fuel burner having in combination a mixing-tube, a hollow body communicating therewith and forming a chamber, a burner-casing surrounding said body 40 and forming therewith a restricted annular passage-way, said body having a series of outlets by which the mixture therein is discharged into the passage-way, and a cap for the casing having a central restricted orifice 45 therethrough, substantially as specified.
20. A gaseous-fuel burner having in combination a mixing-tube, a chamber in communication therewith, a burner-casing surrounding said chamber and forming therewith a restricted annular passage-way, said body having narrow slits therethrough, said casing projecting beyond the chamber and having the projecting end thereof provided with a restricted central outlet, substantially as 50 specified. 55

In testimony whereof I affix my signature in the presence of two witnesses.

JOHN HARRIS.
